(57) **CLAIM**

The ornamental design for a lunch box, as shown and described.

DESCRIPTION

FIG. 1 is a front and top perspective view of a first embodiment of a first piece of a lunch box, showing my new design;

FIG. 2 is a rear and bottom perspective view thereof;
FIG. 3 is a front elevation view thereof;
FIG. 4 is a rear elevation view thereof;
FIG. 5 is a left side elevation view thereof;
FIG. 6 is a right side elevation view thereof;
FIG. 7 is a top plan view thereof;
FIG. 8 is a bottom plan view thereof;
FIG. 9 is a front and top perspective view of a first embodiment of a second piece of the lunch box;
FIG. 10 is a rear and bottom perspective view thereof;
FIG. 11 is a front elevation view thereof;
FIG. 12 is a rear elevation view thereof;
FIG. 13 is a left side elevation view thereof;
FIG. 14 is a right side, elevation view thereof;
FIG. 15 is a top plan view thereof;
FIG. 16 is a bottom plan view thereof;
FIG. 17 is an enlarged view of a portion indicated with numeric 17 in FIG. 9;
FIG. 18 is a front, and top perspective view of a first embodiment of the lunch box showing the first piece is combined with the second piece.
FIG. 19 is a rear and bottom perspective view thereof;
FIG. 20 is a front elevation, view thereof;
FIG. 21 is a rear elevation view thereof;
FIG. 22 is a left side elevation view thereof;
FIG. 23 is a right side elevation view thereof;
FIG. 24 is a top plan view thereof;
FIG. 25 is a bottom plan view thereof;
FIG. 26 is an exploded view thereof;
FIG. 27 is a front and top perspective view of a second embodiment of a first piece of the lunch box;
FIG. 28 is a rear and bottom perspective view thereof;
FIG. 29 is a front elevation view thereof;
FIG. 30 is a rear elevation view thereof;
FIG. 31 is a left side elevation view thereof;
FIG. 32 is a right side elevation view thereof;
FIG. 33 is a top plan view thereof;
FIG. 34 is a bottom plan view thereof;
FIG. 35 is a front and top perspective view of a second embodiment of a second piece of the lunch box;
FIG. 36 is a rear and bottom perspective view thereof;
FIG. 37 is a front elevation view thereof;
FIG. 38 is a rear elevation view thereof;

(Continued)

FIG. 39 is a left side elevation view thereof;
 FIG. 40 is a right side elevation view thereof;
 FIG. 41 is a top plan view thereof;
 FIG. 42 is a bottom plan view thereof;
 FIG. 43 is an enlarged view of a portion indicated with numeric 43 in FIG. 35;
 FIG. 44 is a front and top perspective view of a second embodiment of the lunch box showing the first piece is combined with the second piece.
 FIG. 45 is a rear and bottom perspective view thereof;
 FIG. 46 is a front elevation view thereof;
 FIG. 47 is a rear elevation view thereof;
 FIG. 48 is a left side elevation view thereof;
 FIG. 49 is a right side elevation view thereof;
 FIG. 50 is a top plan view thereof;
 FIG. 51 is a bottom plan view thereof;
 FIG. 52 is an exploded view thereof;
 FIG. 53 is a front and top perspective view of a third embodiment of a first piece of the lunch box;
 FIG. 54 is a rear and bottom perspective view thereof;
 FIG. 55 is a front elevation view thereof;
 FIG. 56 is a rear elevation view thereof;
 FIG. 57 is a left side elevation view thereof;
 FIG. 58 is a right side elevation view thereof;
 FIG. 59 is a top plan view thereof;
 FIG. 60 is a bottom plan view thereof;
 FIG. 61 is a front and top perspective view of a third embodiment of a second piece of the lunch box;
 FIG. 62 is a rear and bottom perspective view thereof;
 FIG. 63 is a front elevation view thereof;
 FIG. 64 a rear elevation view thereof;
 FIG. 65 is a left side elevation view thereof;
 FIG. 66 is a right side elevation view thereof;
 FIG. 67 is a top plan view thereof;
 FIG. 68 is a bottom plan view thereof;
 FIG. 69 is an enlarged view of a portion indicated with numeric 69 in FIG. 61;
 FIG. 70 is a front and top perspective view of a third embodiment of the lunch box showing the first piece is combined with the second piece.
 FIG. 71 is a rear and bottom perspective view thereof;
 FIG. 72 is a front elevation view thereof;
 FIG. 73 is a rear elevation view thereof;
 FIG. 74 is a left side elevation view thereof;
 FIG. 75 is a right side elevation view thereof;
 FIG. 76 is a top plan view thereof;
 FIG. 77 is a bottom plan view thereof;
 FIG. 78 is an exploded view thereof;
 FIG. 79 is a front and top perspective view of a fourth embodiment of a first piece of the lunch box;
 FIG. 80 is a rear and bottom perspective view thereof;
 FIG. 81 is a front elevation, view thereof;
 FIG. 82 is a rear elevation view thereof;
 FIG. 83 is a left side elevation view thereof;
 FIG. 84 is a right side elevation view thereof;
 FIG. 85 is a top plan view thereof;
 FIG. 86 is a bottom plan view thereof;

FIG. 87 is a front and top perspective view of a fourth embodiment a second piece of the lunch box;
 FIG. 88 is a rear and bottom perspective view thereof;
 FIG. 89 is a front elevation view thereof;
 FIG. 90 is a rear elevation view thereof;
 FIG. 91 is a left side elevation view thereof;
 FIG. 92 is a right side elevation view thereof;
 FIG. 93 is a top plan view thereof;
 FIG. 94 is a bottom plan view thereof;
 FIG. 95 is an enlarged view of a portion indicated with numeric 95 in FIG. 87;
 FIG. 96 is a front and top perspective view of a fourth embodiment of the lunch box showing the first piece is combined with the second piece.
 FIG. 97 is a rear and bottom perspective view thereof;
 FIG. 98 is a front elevation view thereof;
 FIG. 99 is a rear elevation view thereof;
 FIG. 100 is a left side elevation view thereof;
 FIG. 101 is a right side elevation view thereof;
 FIG. 102 is a top;plan view thereof;
 FIG. 103 is a bottom plan view thereof; and,
 FIG. 104 is an exploded view thereof.
 The dash dot dash lines in FIGS. 9, 17, 35, 43, 61, 69, 87 and 95 are for the purpose of depicting the boundary lines of the enlarged views and form no part of the claimed design.
 the first piece and the second piece of each embodiment is shown separated for clarity of illustration.
